UNITED STATES PATENT OFFICE.

EDWARD M. JUDD, OF NEW BRITAIN, CONNECTICUT, ASSIGNOR TO HUBERT L. JUDD, OF SAME PLACE.

IMPROVED CURTAIN-FIXTURE.

Specification forming part of Letters Patent No. 40,381, dated October 20, 1863.

To all whom it may concern:

Be it known that I, EDWARD M. JUDD, of New Britain, in the county of Hartford and State of Connecticut, have invented, made, and applied to use a certain new and useful Improvement in Curtain-Fixtures; and I do hereby declare the following to be a full, clear, and exact description of my said invention, reference being had to the annexed drawings, making part of this specification, wherein—

Figure 1 is a sectional plan of the end of the curtain-roller and of the bracket, and Fig. 2 is an end view of the pin on which the tape is wound as the shade or curtain is drawn down. Similar letters denote the same parts.

Curtain-fixtures have heretofore been made with a pin cast upon the metallic end piece of the roller, and in this pin a hole has been bored to receive the end of a tape by which the curtain can be rolled up, and which tape is wound upon said pin in the act of drawing down the curtain.

The nature of my said invention consists in a pin in which a slot or mortise is cast, and which pin passes into the end of the roller and holds on the metal end piece. By this means cost of drilling is avoided, and a much better hole is formed for the introduction of the tape, the metallic end of the roller is held on without requiring separate nails, and the pin itself is much stronger and more secure in consequence of entering the roller.

In the drawings, *a* is the roller receiving the curtain *b*. *c* is the metallic end of the roller, in the center of which is a hole to pass the pin *d*, that forms the journal for the roller and revolves in a socket in the bracket *e*. This pin *d* has a mortise, 1, cast through it, into which the tape or cord *f* is entered and fastened by a knot or otherwise, and 2 is a shoulder on said pin, which, taking the metallic end *c*, holds the same firmly to the roller. The end of the pin *d* that enters the roller should be tapering, so as to drive in; and one or two screw-threads may be formed around said pin, either to aid in holding the same firmly in the roller or to allow the pin to be screwed in instead of being driven in.

My device is simple, cheap, and easily applied, and overcomes difficulties heretofore experienced with curtain-fixtures of this general character.

What I claim and desire to secure by Letters Patent is—

The pin *d*, formed with the mortise 1, for receiving the tape, and with the shoulder 2 for securing the metallic end *c* to the roller *a*, as specified.

In witness whereof I have hereunto set my signature this 5th day of September, 1863.

E. M. JUDD.
